LUBRICATING DEVICE FOR SEWING
MACHINE LOOP TAKERS

Walter Myers, Bridgeport, Conn., assignor to The
Singer Manufacturing Company, Elizabeth,
N. J., a corporation of New Jersey

Original application October 14, 1939, Serial No.
299,415. Divided and this application October
25, 1940, Serial No. 362,744

2 Claims. (Cl. 112—256)

This invention relates to sewing machine loop-takers, and more particularly to loop-takers of the vertical-axis rotary hook type having a raceway providing a bearing for a thread-carrier journaled in the loop-taker and restrained against rotation therewith.

The present invention has for its object to provide improved means for supplying lubricant to the thread-carrier raceway of a vertical-axis type of loop-taker to minimize friction-induced heating of the loop-taker.

With the above and other objects in view, as will hereinafter appear, the invention comprises the devices, combinations, and arrangements of parts hereinafter set forth and illustrated in the accompanying drawing of a preferred embodiment of the invention, from which the several features of the invention and the advantages attained thereby will be readily understood by those skilled in the art.

In the accompanying drawing, Fig. 1 is a top plan view of the loop-taker end portion of the bed-plate of a two-needle sewing machine containing the present improvements, the throat-plate and side slide-plates of the bed-plate being removed. Fig. 2 represents a perspective view of the bobbin-carrier. Fig. 3 is an enlarged vertical section of portions of one of the loop-takers and its bobbin-carrier, the section being taken substantially on the line 3—3, of Fig. 1.

This application is a division of application Serial No. 299,415, filed Oct. 14, 1939, which has resulted in Patent No. 2,236,830, dated April 1, 1941.

The sewing machine shown in the drawing has a frame including a work-supporting bed-plate 10 provided with an elongated opening 11 exposing the loop-taker mechanisms disposed below the bed-plate. The machine illustrated in the drawing as containing the present improvement has two loop-takers which are substantially alike in construction and mode of operation, so that the description of one of the loop-takers is equally descriptive of the other.

The loop-taker 12 has a cup-shaped body provided with a loop-seizing beak 13. The inner side face of the loop-taker body, at the upper or rim portion thereof, is partly cut away to provide a shouldered recess constituting a thread-carrier raceway comprising a vertically cylindrical bearing-wall 14 and a horizontally extending bearing-ledge 15.

Journalized in the loop-taker raceway is an interrupted bearing-rib 16 of a thread-carrier 17,

said bearing-rib being retained in the loop-taker raceway by a substantially flat gib 18 detachably secured upon the loop-taker rim by screws 19. The gib is constructed substantially like that more fully disclosed in my prior U. S. Patent No. 1,917,771, July 11, 1933. One end of the interrupted bearing-rib 16 of the thread-carrier provides a vertically inclined thread-loop detaining shoulder 20.

The thread-carrier 17 has an interrupted peripheral flange 21 spaced vertically from the bearing-rib 16 and also overhanging the thread-carrier retaining gib 18 of the loop-taker, said gib 18 extending into the circumferential recess or groove formed in the outer wall of the thread-carrier by the vertically spaced flange 21 and bearing-rib 16 thereof. The flange 21 has a beveled or vertically inclined portion 22 at the thread-loop cast-on side of the thread-carrier directly above the end portion of the bearing-rib 16 which provides the thread-loop detaining shoulder 20 of the thread-carrier.

Adjacent its opposite end, the flange 21 of the thread-carrier is provided with an upwardly open oil-pocket 23 elongated circumferentially of the thread-carrier and preferably containing an oil-absorbent material 24. By providing the oil-pocket in the peripheral flange 21, the size of the pocket may be made large enough to hold a substantial quantity of lubricant, without modifying the thread capacity of the thread-carrier.

Opening into the bottom wall of the oil-pocket 23 is the upper end of a vertical oil-duct 25 formed by an aperture provided in the portion of the side wall of the thread-carrier between the flange 21 and the bearing-rib 16. The lower end of the vertical oil-duct 25 terminates in the inner end of a radial oil-duct aperture 26 extending horizontally through the bearing-rib and open at its outer end to the loop-taker raceway. The oil-pocket 23 being open at the top thereof, the oil may be conveniently supplied thereto as required, and the oil contained in the wick-filled pocket 23 will gravitationally find its way into the vertical duct 25 and will then be supplied to the loop-taker raceway through the duct 25. It will thus be noted that the oil is confined to pass from the oil-pocket 23 to said raceway.

As more fully explained in my prior application Serial No. 299,415, the thread-carrier 17 is restrained against rotation with the loop-taker 12 by horizontally arcuate fingers 27 of a rocking escapement device, said fingers being adapted to enter arcuate apertures 28 provided in the

flange 21 of the thread-carrier 17 at substantially diametrically opposing sides of the thread-carrier. By restraining the thread-carrier against rotation with the loop-taker, the tendency is to overheat the parts because of bearing friction. The present improvement provides simple means for reducing the friction-induced heating to a minimum.

Having thus set forth the nature of the invention, what I claim herein is:

1. A vertical-axis rotary loop-taker for sewing machines, having a cup-shaped body provided with a thread-carrier raceway, a thread-carrier having a peripheral bearing-rib journaled in said raceway and having a peripheral flange overhanging said bearing-rib, said flange being spaced vertically from said bearing-rib and provided with an upwardly open oil-pocket lengthwise extending circumferentially of said thread-carrier, a gib secured upon said rotary loop-taker and disposed between said bearing-rib and flange of the thread-carrier, an oil-duct in the side wall of said thread-carrier extending downwardly from the bottom wall of said oil-pocket, and a radial oil-duct in said thread-carrier connecting said downwardly extending oil-duct with said raceway of the loop-taker.

2. A vertical-axis rotary loop-taker for sewing machines, comprising an upwardly open cup-shaped body having its inner face at the rim portion thereof cut away to provide a circumferentially extending vertical bearing-wall and a circumferentially extending horizontal bearing-ledge together forming a thread-carrier raceway, a thread-carrier having a peripheral bearing-rib journaled in said raceway, a peripheral flange extending from said thread-carrier and provided with an upwardly open and wick-filled oil-pocket, said flange being spaced vertically from and overhanging said bearing-rib, thereby forming a circumferential recess in the outer wall of said thread-carrier between said flange and bearing-rib, a gib detachably secured upon the rim of said loop-taker and extending into said recess, an oil-duct extending through said bearing-rib from the outer face thereof and terminating at its inner end in the side wall of said thread-carrier, and an oil-duct connected with the bearing-rib oil duct and extending downwardly from said oil-pocket within the side wall of said thread-carrier between said flange and bearing-rib.

WALTER MYERS.
